UNITED STATES PATENT OFFICE

HORACE N. STEVENSON, OF TRENTON, NEW JERSEY

ADJUSTABLE SPRINGBOARD

Application filed November 1, 1932. Serial No. 640,712.

This invention relates to new and useful improvements in spring boards and has particular relation to such apparatus wherein the spring board anchorage may be varied with respect to the fulcrum about which said board pivots.

The principal object of the invention is to provide a spring board of the character set forth having novel means associated therewith whereby the distance between the spring board anchorage and the fulcrum point may be varied to enable the degree of spring in said board to be adjusted to meet the requirements of persons of various weights who may use the board.

A more specific object of the invention is to provide an adjustable spring board of the character set forth wherein the fulcrum remains in a fixed position and the adjustment is obtained by moving the board therealong to change the relative position of the spring board anchorage with respect to said fixed fulcrum.

A further object of the invention is to provide an adjustable spring board of the character set forth wherein the angle at which the spring board proper is disposed with respect to the water or other surface, is maintained constant at all times, regardless of the relative position of the spring board anchorage with respect to the fixed fulcrum.

A further object of the invention is to provide an adjustable spring board of the character set forth which is rugged in construction and capable of withstanding long and hard usage out of doors when exposed to the elements of nature.

Other features and details of the invention are set forth hereinafter and disclosed in the accompanying drawing, in which:

Figure 1 is a view in perspective of the device constituting the present invention;

Fig. 2 is an enlarged longitudinal view in section through the spring board;

Fig. 3 is a rear end elevation of the invention; and

Fig. 4 is a view in front elevation of the spring board showing the construction of the fixed fulcrum.

Referring now more particularly to the

drawing, the spring board constituting the present invention comprises a supporting structure including front and rear spaced standards 1 and 2, and conveniently located structural brace members 3. In the present instance the front supporting standards 1 are of greater height than the rear supports 2, for the purpose of disposing the spring board at an angle with respect to the water or other surface. Tubular support members 4 and 5 extend longitudinally between and are welded integral with the vertical standards 1 and 2 at each side of the supporting structure, as shown in Fig. 1, and as will be noticed by reference to the drawing, said tubes 4 and 5 extend a short distance outwardly beyond the standards 1.

A cylindrical or tubular cross member 6 is secured intermediate the projecting ends of the tubes 4 and 5 and is supported in fixed relation with respect thereto by means of structural members 7 in the form of pipe L's or the like. A sleeve 8 is rotatably mounted on the member 6 intermediate the abutments formed by the radially disposed adjacent end surfaces of the pipe L's 7. The rotatable sleeve 8 is provided with a snugly fitting outer sleeve or covering 9 composed of rubber or other suitable material. The structure described immediately above comprises the fulcrum assembly of the spring board, and the rotatable sleeve 8 constitutes a roller on which the spring board proper may ride and the rubber covering 9 thereon functions as a cushion or snubber for said board when the latter vibrates thereagainst.

Sleeves 10 and 11 of substantial length are slidably mounted respectively in the tubes 4 and 5 and are arranged to move longitudinally with respect thereto in telescopic manner, the said sleeves 10 and 11 forming part of an extensible carriage the purpose for which will be set forth hereinafter. A cross member 12 is connected intermediate the rearwardly projecting extremities of each of sleeves 10 and 11 and is supported in fixed relation with respect thereto by means of fittings 13, such as L to T pipe sections in the manner disclosed in Fig. 3 of the drawing.

A screw shaft 14 is rotatably mounted in the sleeve 11 and is supported at its outer end by means of a flanged collar 15 journaled in the fitting 13 on the sleeves 11 and at its 5 opposite or inner end by the threaded nut 16 which is rigidly secured to the inner side walls of the sleeve 11 adjacent the forward end thereof. A centering block 17, composed in the present instance of wood, is secured 10 internally of the sleeve 11 adjacent the forward or inner end thereof for the purpose of directing or piloting the screw shaft 14 into the threaded nut 16 when the assembly has been entirely removed and it is desired to 15 again assemble the same. A hand wheel 18 or other means capable of imparting rotation in both a clockwise and counter-clockwise direction to the screw shaft 14, is secured on the outer or rear extremity of said shaft 20 by means of a key or set screw (not shown).

For the purpose of firmly securing the particular adjustment of the carriage at a desired position and for the purpose of eliminating possible rattle of the associated parts 25 thereof, it has been found desirable to provide one or more set screws 19, (see Fig. 2) which are threaded in the side wall of the tubular member 5, and which, when tightened, will bind against the outer side surface 30 of the inner slidable sleeve 11, thus securing the latter firmly in position.

A spring board proper 20 is rigidly secured or anchored at its rear end to the end cross member 12 by means of bolts 21, and extends 35 longitudinally with respect to the supporting structure and rests upon the roller fulcrum, which has been previously described, the said board 20 being of such length as to extend appreciably beyond the fulcrum point as 40 shown in Fig. 1 of the drawing.

In operation of the device, it will be readily seen that rotation of the hand wheel 18 in one direction will cause the sleeves 10 and 11 to emerge from the tubes 4 and 5 toward 45 the rear of the structure, resulting in a corresponding simultaneous movement of the spring board 20 in the same direction to increase the relative distance between the spring board anchorage point and the fixed 50 fulcrum, thus rendering the spring board more rigid for use by persons of more than average weight, and a movement of the hand wheel 18 in the opposite direction, moves the sleeves 10 and 11 inwardly of the tubes 4 and 55 5 and advances the carriage and the spring board anchorage to a point in closer proximity to the fixed fulcrum, rendering the spring board 20 capable of greater flexibility for use 60 by persons of relatively light weight.

It will be noted that by virtue of the novel construction employed in the present invention, the angle at which the spring board 20 is disposed with respect to the horizontal will 65 be the same at all times, irrespective of the

relative position of the spring board anchorage with respect to the fixed fulcrum.

While the particular embodiment of the invention has been set forth for the purposes of description, it is not intended that the 70 precise structural limitations set forth be adhered to except such as are not within the scope of the appended claims.

What is claimed is:

1. In an apparatus of the stated character, 75 a frame including a fulcrum member, a carriage movable with respect to said frame, a spring board resting on said fulcrum and anchored at one end to the carriage, and means for adjusting the carriage with respect to the frame, to vary the relative positions of the spring board anchorage and the fulcrum with respect to each other and increase or decrease the effective rigidity of the board. 80

2. In apparatus of the stated character, 85 the combination with a frame, of a roller constituting a fulcrum secured in fixed relation at one end thereof, a carriage adjustable longitudinally at a fixed angle with respect to the frame, a spring board resting on said 90 fulcrum and anchored to the carriage, and means for adjusting said carriage with respect to the frame to vary the relative position of the spring board anchorage with respect to the fulcrum, the angular position 95 of the spring board with respect to the horizontal remaining fixed regardless of the relative position of the spring board anchorage and the fulcrum.

3. In apparatus of the stated character, 100 the combination with a frame, of a roller constituting a fulcrum secured in fixed position at one end thereof, supports at the upper edge of each side of the frame, extensible 105 means slidably mounted in said supports, a spring board secured at one end to said extensible means and resting on the roller fulcrum, and means operable to move the extensible means with respect to the frame to vary the relative position of the spring board 110 anchorage with respect to the fulcrum and increase or decrease the effective rigidity of the board. 110

4. In apparatus of the stated character, 115 the combination with a frame, of a fulcrum secured in fixed position at one end thereof, supports at the upper edge of each side of the frame, extensible means slidably mounted in said supports, a spring board secured at one end to said extensible means and resting 120 on the fulcrum, and means operable to move the extensible means with respect to the frame to vary the relative position of the spring board anchorage with respect to the fulcrum and increase or decrease the effective 125 rigidity of the board. 125

5. In apparatus of the stated character, 130 the combination with a frame, of a fulcrum secured in fixed position at one end thereof, a tube at the upper edge of each side of the

frame, and declining at a small angle in a direction away from said fulcrum, extensible means slidably mounted in said tubes, a spring board secured at one end to said extensible means and resting on the fulcrum, and means operable to adjust the extensible means with respect to the frame to vary the relative position of the spring board anchorage with respect to the fulcrum, the angular position of the spring board with respect to the horizontal remaining constant at all times.

6. In apparatus of the stated character, the combination with a frame, of a fulcrum secured in fixed position at one end thereof, a tube at the upper edge of each side of the frame, extensible means slidably mounted in said tubes, a spring board secured at one end to said extensible means and resting on the fulcrum, and means operable to adjust the extensible means with respect to the frame to vary the relative position of the spring board anchorage with respect to the fulcrum.

7. In apparatus of the stated character, the combination with a frame, of a fulcrum member secured in fixed position at one end thereof, extensible means movably mounted on said frame and disposed at a small angle with respect to the horizontal, a spring board secured at one end to the said extensible means and resting on the fulcrum member, and a screw shaft operatively connected between said extensible means and the frame to adjust the latter with respect to said frame to vary the relative position of the spring board anchorage with respect to the fulcrum, the angular position of the spring board remaining constant at all times.

8. In apparatus of the stated character, the combination with a frame, of a fulcrum member secured in fixed relation at one end thereof, a tube at the upper edge of each side of the frame, extensible means movably mounted in said tubes, a spring board secured at one end to said extensible means and resting on the fulcrum member, and a screw shaft operatively connected between said extensible means and the frame to adjust the latter with respect to said frame to vary the relative position of the spring board anchorage with respect to the fulcrum.

9. In apparatus of the stated character, the combination with a frame, of a roller constituting a fulcrum secured in fixed position at one end thereof, a tube at the upper edge of each side of the frame and declining at a small angle in a direction away from the roller, a sleeve forming part of a carriage slidably mounted in each of said tubes and connected at their outer ends by a cross piece, a spring board secured at one end to said cross piece and resting on the roller fulcrum, and a screw shaft journaled in one of said sleeves and cooperating with a threaded nut secured in the tube to slide the carriage longitudinally

with respect to said frame and vary the relative position of the spring board anchorage with respect to the roller fulcrum to increase or decrease the effective rigidity of the board.

10. In apparatus of the stated character, the combination with a frame, of a roller constituting a fulcrum secured in fixed position at one end thereof, a tube at the upper edge of each side of the frame and declining at a small angle in a direction away from the roller, a sleeve forming part of a carriage slidably mounted in each of said tubes, a spring board secured at one end of said carriage and resting on the roller fulcrum, and a screw shaft journaled in one of said sleeves and cooperating with a threaded nut secured in the tube to slide the carriage longitudinally with respect to said frame and vary the relative position of the spring board anchorage with respect to the roller fulcrum to increase or decrease the effective rigidity of the board.
